UNITED STATES PATENT OFFICE.

BERNHARD TROPP, OF NEW YORK, N. Y., ASSIGNOR TO WILLIAM HENRY LAIRD, OF NEW YORK, N. Y.

SELF-WINDING ELECTRIC CLOCK.

No. 821,140.

Specification of Letters Patent.

Patented May 22, 1900.

Application filed July 16, 1898. Serial No. 216,817.

To all whom it may concern:

Be it known that I, BERNHARD TROPP, a citizen of the United States, and a resident of New York, in the county of New York and State of New York, (whose post-office address is 193 Greenwich street,) have invented certain new and useful Improvements in Self-Winding Mechanism for Clocks, of which the following is a specification.

10 My invention relates to an improved self-winding device for clocks or other devices driven by a spring or weight and in which the winding device consists of an electric motor periodically thrown into action and automatically thrown out of action when a sufficient amount of power has been stored.

One of the special objects of my invention is to secure a device by means of which power shall be stored to exactly the same amount 20 for each application of the winding power.

Another object of my invention is to produce a device which shall be simple and effective in operation and capable of being readily used with or applied to any ordinary spring-driven train of wheels—like, for instance, a clock-train.

My invention relates more particularly to the circuit closing and breaking devices which throw the electric motor into and out of action 30 and involves the employment of a pair of circuit closing and breaking devices, one of which is a primary circuit-closer operated by the driven mechanism and the other of which is a secondary circuit-closer operated from some portion of the winding mechanism and which comes into action as soon as said winding mechanism is brought into action by the 35 action of the primary circuit-closer and maintains the circuit until the winding has progressed to a predetermined or exact amount, when said secondary circuit-closer breaks the circuit, the primary circuit-closer in the meantime having also broken said circuit.

My invention consists in the novel combination of apparatus and details of construction more particularly hereinafter described, and then set forth in the claims.

In the accompanying drawings, Figure 1 is a side elevation of an apparatus embodying my invention and shows the same as applied to a clock. Fig. 2 is an end elevation of the same apparatus. Fig. 3 is a detail showing the circuit-closing devices in plan.

1 indicates a frame of the usual character

in which is mounted a suitable time-train 53 driven by a suitable spring 3, one end of which is secured to a shaft carrying the wheel 2, gearing with the time-train, as well understood in the art.

4 is the mainspring-barrel, by turning 60 which the spring may be wound up. Connected to said barrel is a wheel 5, to which a single turn is given periodically for the purpose of keeping the spring wound. The winding power is obtained from an electric 65 motor geared to the wheel 5 in any suitable manner, said motor being of any desired construction.

In the present instance I have shown my invention carried out with a vibratory or reciprocating electric motor of ordinary type and comprising an electromagnet 6, whose armature 7 is secured to a lever 8, pivoted at 9 and carrying at its lower end a pawl 10, which as the lever vibrates turns the serrated 70 wheel 11. Said wheel 11 is geared in obvious manner, through the train 12, 13, 14, 15, and 16, with the wheel 5. A suitable click 17 prevents reverse movement of the wheel 11 and the winding-train. The armature 7 75 bridges the electromagnetic heads of the electromagnet 6, as shown, and the spring 19 serves to force the armature away from the magnet and in so doing causes partial movement of the wheel 11 of the winding-train, 80 which movement is repeated through the automatic action of the circuit closer and breaker, the points of which are indicated at 20 and which is of the ordinary construction adapted to close the circuit of the electro- 85 magnet when the armature is retracted and to break the same when the armature is thrown forward, thus securing a repetition of the action in the same manner as in any ordinary vibratory alarm-bell. The train of 90 wheels between the magnet and wheel 5 is simply for the purpose of giving the mechanical advantage to the magnet and permitting the use of a small magnet or motor to wind the spring. Suitable adjustments of obvious 95 character and function are provided, by means of the stop-screws 21 and 22, for the contacts at 20 and for the spring 19, as well understood in the art. The motor just described will operate so long as current is supplied thereto by closing the circuit or connection between the same and any source of electric energy.

105

23 is the contact-spring of what I term the "primary" circuit-closer, by means of which the circuit of the motor is closed and broken. Said spring, like the spring 24 of what I term 5. a "secondary" circuit-closer, may be fastened, as indicated, to a suitable block 25, of insulating material, mounted in the framework or in any other suitable way. These springs may be formed in or from the same 10 piece of metal, since they both close the same circuit for the electric motor. Mounted on some portion of the driven train—as, for instance, the hour-wheel 26 of the clock—is a contact 27, which at every hour passes and 15 engages the spring 23 and closes the circuit for the motor, owing to the fact that the train of wheels and the framework of the clock are made a part of the circuit, as usual in the art. The spring 24 closes the same 20 circuit by the action of some device connected with the winding mechanism or train. For convenience and simplicity I propose to employ for this purpose the mainspring-drum 4, which is provided at some point in 25 its periphery with the notch 28 or other insulating-space which breaks the circuit when the winding has been accomplished. As soon as the winding begins again the insulating-space passes from under the spring 24, 30 and the latter then closes circuit on the periphery of the drum. By placing the stud 27 on the hour-wheel it is obvious that the winding would take place hourly only. It is plain, however, that said stud might be located on some other wheel of the train, so as 35 to close the circuit of the motor at more frequent intervals. By causing the break and closing of circuit by means of spring 24 to take place by means of the mainspring- 40 drum, as shown, having but one circuit-breaking space 28, it is obvious that at each winding the spring will be wound up one whole turn. It is plain, however, that the secondary circuit-closer 24 might be operated 45 from some other part of the winding train or mechanism, so that the spring would be wound up to a less extent for every time that the motor is brought into action. There is, however, an advantage in operating the primary and secondary circuit-closers in the 50 manner described by means of the winding-drum and the hour-wheel, since they may then be located at the same point and form parts of the same piece of metal secured to 55 the same support, thus giving compactness and simplicity of construction. It will also be obvious that by operating said circuit-closers by the means described I am enabled to readily apply my invention to existing 60 clock mechanisms, it being only necessary to insert a stud 27 in the hour-wheel and to locate a slot 28 in the mainspring-drum, as described, the mainspring-shaft being provided also with a winding-wheel 5.

65 The circuits may be formed in any desired way. Thus, for instance, the armature-lever 8 or the support for the pivot thereof may be in electrical connection through the frame and wheel work with the parts which engage and make electric contact with the springs 70 23 and 24. The back-contact screw 21 for said armature may be mounted upon an insulated post, as shown in Fig. 2, and be electrically connected with one terminal of the coil of electromagnet 6, the other terminal being connected to a battery or other source of electrode energy. The two springs 23 24 on the support insulated from the framework may be electrically connected in any suitable way with the pole of the source opposite that 80 to which the coil of the electromagnet is connected.

The operation of the apparatus would be as follows: Normally the mechanism would be in condition indicated in Fig. 1, in which, 85 as shown, the wheel 26 is performing its rotation in the direction of the arrow under the power of the spring 3. The spring 24 of the secondary circuit-closer has its end resting in the notch 28, and inasmuch as the stud 27 90 has in the condition of the apparatus shown left the spring 23 there is no circuit completed through the motor, the armature-lever of which, 8, rests against its back contact. When the wheel 26 rotates sufficiently to 95 bring the stud 27 in wiping contact with the end of the spring 23, the circuit of the motor will be closed and the latter will immediately begin to wind the spring 3 and will continue to wind it until by the movement of the 100 drum 4 of the winding mechanism the circuit for the motor has been closed by the secondary closer 24. In the meantime the pin 27 momentarily maintains a closure of circuit on the spring 23 and until the circuit has 105 been closed by spring 24, at any desired time after which the stud or pin 27 may open the circuit on the spring 23, which it will proceed to do, inasmuch as the wheel 26 maintains its constant movement, owing to the provision 110 of a considerable surplus or reserve power in the spring 3 over and above that necessary to produce a single revolution of the wheel 26. The circuit of the motor is now maintained by the spring 24 and the winding goes on 115 until by the movement of the winding mechanism the notch or insulating-space 28 has been brought under the end of the spring 24, whereupon the circuit of the motor is interrupted, owing to the fact that the circuit 120 on the primary circuit-closer 23 has in the meantime been interrupted by the movement of the wheel 26 and pin 27. The winding then ceases to be repeated, when the power of the spring 3 has been expended sufficiently 125 to cause the circuit to be again closed on the primary circuit-closer.

While I have described my invention as applied to the winding up of a spring, it is obvious that it might be used for periodically 130

restoring the driving power of any other device. It is also obvious that my invention is not limited to use with the driving power for a clock, but might be used with the driving power for any mechanism.

5 What I claim as my invention is—

1. The combination substantially as described of a driving power, a driven mechanism, an electric motor, winding mechanism interposed between the same and the driving power, a primary circuit-closer, comprising a stationary contact member and a coöperating contact member carried by a wheel of the driven mechanism for periodically but momentarily closing the circuit of the motor at one point, and a secondary independently-operating circuit-closer comprising a fixed contact member and a coöperating contact member carried by a wheel connected with the winding mechanism.
- 10 2. The combination in a self-winding mechanism of a spring-driven train, an electric motor for periodically winding said spring, a circuit-closing device in the circuit of said motor comprising a pin or projection on a wheel of the driven train and a spring, periodically but momentarily engaged thereby, and a second circuit-closer in the circuit of said motor, comprising the barrel of the spring having an insulating-space, and coöperating spring engaging said barrel.
- 15 3. The combination with a time-keeping device, of a winding electric motor, primary circuit-closer, in the circuit of said motor, consisting of a contact-pin set in the hour-wheel of the train and adapted to engage a circuit-closing spring, and a secondary circuit-closer comprising a spring-barrel having

an insulating notch or space and a coöperating circuit-closing spring, as and for the purpose described.

4. In a self-winding mechanism for clocks, the combination with an electric motor and a winding-barrel operated by said motor, of a primary circuit-closer comprising a pin or stud projecting from a wheel of the clock-train and adapted to engage a coöperating circuit-closing spring, and a secondary circuit-closer consisting of a winding-barrel having an insulated space and a coöperating contact-spring adapted to engage said barrel.

5. In a winding mechanism for spring-driven timepieces, the combination of an electric motor, a winding-train interposed between the same and the spring, a secondary circuit-closer brought into action by a revolving member of the winding-train when the winding starts, and a primary circuit-closer brought into action by a pin or stud projecting from a wheel of the time-train and adapted to close the circuit of the motor to start the winding.

6. In a self-winding mechanism for clocks, the combination of an electric motor and two circuit-closers therefor, one consisting of a spring 23 and a stud 27 on the hour-wheel of the clock, and the other consisting of a spring 24 engaging the periphery of the notched spring-barrel.

Signed at New York, in the county of New York and State of New York, this 6th day of July, A. D. 1904.

BERNHARD TROPP.
